Specification of Letters Patent.

Patented July 9, 1918.

Application filed November 24, 1913, Serial No. 802,728. Renewed December 14, 1916. Serial No. 137,062.

To all whom it may concern:

Be it known that I, ZENOPHILE BISAUILLON, a subject of the King of Great Britain, residing at Laprairie, in the county of Laprairie and Province of Quebec, Dominion of Canada, have invented certain new and useful Improvements in Keyless Locks; and I do hereby declare that the following is a full, clear, and exact description of the same.

10 For full comprehension, however, of my invention reference must be had to the accompanying drawings forming a part of this specification in which similar reference characters indicate the same parts, and

15 wherein: Figure 1 illustrates in side elevation, the invention applied to a railway car or warehouse door, the door proper being shown in the act of being opened, and with the 20 parts indicated by dotted lines positioned ready for locking and locked respectively; and

Fig. 2 is a detail perspective view of the vibratory member.

25 Fig. 3 is a sectional view taken on line A A Fig. 1;

Fig. 4 is an enlarged detail elevation of the lever having a hook at one end and a quadrantal rack at the other adapted to engage the device on the door frame;

Fig. 5 is an underside perspective view of the tumbler operated by the hook;

Fig. 6 is a sectional view taken on line B B Fig. 4;

35 Fig. 7 is an enlarged detail perspective view of the member for disengaging the locking devices;

Fig. 8 is a detail perspective view of the member adapted to engage the main 40 knocker;

Fig. 9 is a detail perspective view of the combination pinion and ratchet wheel; and

Fig. 10 is a sectional view taken on line C C Fig. 9.

45 My invention relates particularly to locks for sliding doors such as used for freight cars, storage warehouses and the like; and it has for its object to provide a key-less lock of this type.

50 The invention may be said to consist of the combination with engaging locking devices proper, of a vibratory member opera-

tively connected to the locking device and requiring a plurality of operations before the locking devices are detached.

55

The door casing is indicated at *b* and a sliding door at *c*, one of the locking devices is of course carried by the door and the device with which it engages by the door frame, each being mounted on an independent casing indicated at *e* and *f* respectively.

60

Within the casing upon the door, is mounted on a pivot pin *g*, a lever *h* having a hook *i* at one end, which projects through one end of the casing and the opposite end is in the form of an open frame *k* provided with an internal quadrantal rack *m* concentric with the pivot *g*.

65

This is the locking lever proper and it is operated to move intermittently in a plurality of steps by means to be presently described, the hook end thereof engaging a rigid lug *n* mounted within the casing upon the door frame.

70

Within this last mentioned casing there is also mounted a lever *o* fulcrumed on a fixed pin *p* and having a plunger *q* pivoted thereto by a hinge joint *r*, this plunger projecting through the end of its casing toward the door and being adapted to bear upon the casing on the latter and afford means whereby through the lever *o* the operator may displace the door from locked position when the locking devices are disengaged. This lever *o* also has a lateral extension *s* adapted to come in contact with the contiguous side of the casing and retain the lever in vertical position.

75

80 A tumbler *t* is operated by the lever *h* and for this purpose is formed with an arm *u* with upward curved end *v*, such arm resting upon the top of the hook *i*; the lower end of the tumbler having a downwardly turned angular arm *w* projecting into an aperture *x* on a tongue *y* rigidly mounted upon the casing *e*.

85

80 The means for operating the lever *h* consists of a vibratory lever *2*, fulcrumed upon a rigid pin *3* mounted on the casing. On this pin *3* is rotatively mounted a spur pinion *4* having formed integrally therewith a ratchet-wheel *5*, the pinion intermeshing with the quadrantal rack *m* and the ratchet-wheel overlapping the rack and being en-

90

95

100

gaged by a pawl 6. This pawl is formed on the inner end of a lever 7, held away from the lever 2 by a spring 30 and having a forked member 9 through which it is fulcrumed as at 8 to the lever 2, an upright arm 10 being carried by a lateral extension 12 from the forked portion and having a frame 13 curved concentrically to the fulcrumed pin 3 and provided with a series of teeth 14, preferably three in number. A rigid finger 15 is carried by this lever 7 and formed integrally therewith, its purpose being to afford a covering for the opening in the casing which the oscillatory movement of the lever 2 necessitates. The finger 15 is extended downwardly as at 32, the lower end whereof is formed with a stop 33, limiting the upward movement of the lever 7 relatively to the lever 2.

Operation.

In order to lock a door furnished with my invention it is only necessary to close it, the locking operation being automatic.

25 To unlock the door the operator pulls lever o with one hand and at the same time vibrates lever 2 with his other hand pressing lever 7 into contact with lever 2 on the downward stroke and releasing it on the upward stroke. The effect is that on the downward stroke the pawl 6 is made to engage the ratchet-wheel 5 and rotates it about one quarter turn, the spur pinion rotating with it and engaging the quadrantal rack and working it a distance of one tooth, this taking place upon each downward stroke of lever 2 , thus requiring about 30 vibrations to feed the rack to its lowermost position. Simultaneously the hook end of the lever h will be raised until it is disengaged from the lug n and the tumbler t is lifted with it and its arm w disengaged from the aperture x . Immediately the parts assume this position, the pull exerted by the operator on lever o causes the plunger q to push against casing e and open the door sufficiently to place the hook i over lug n and the engaging arm w over the solid end of tongue y , thus preventing the reengaging of these locking devices. The door is then free to be slid open.

I do not herein claim the alarm as such will form the subject-matter of an application to be subsequently filed.

55 What I claim is as follows:—

1. In a lock for sliding doors the combination with inter-engaging locking devices of a vibratory member operatively connected to one of the locking devices, and
60 means intermediate of the member and locking device and requiring a plurality of vi-

brations of the vibratory member to disengage the locking devices.

2. In a lock for sliding doors the combination with inter-engaging locking devices; of means for disengaging the said devices, said means consisting of a manually-operated vibratory lever, a pinion mounted upon one end of said lever, a rack upon one of said devices and intermeshing with the pinion and means constructed and arranged to prevent rotation of the pinion relatively to the rack when the lever is moved in one direction and to permit rotation of the pinion when the lever is moved in the opposite direction. 65 70 75

3. In a lock for sliding doors, the combination with inter-engaging locking devices consisting of a fixed device and a hook fulcrumed substantially midway its length and 80 having a rack on one end thereof; of means for disengaging the said devices, said means consisting of a manually operated vibratory lever having a forked end, a pinion pivotally mounted within the forked end 85 and having a ratchet wheel formed integrally therewith, said pinion intermeshing with the rack and a pawl carried by said lever and constructed and arranged to engage the ratchet wheel for the purpose of 90 preventing rotation of the pinion relatively to the rack when the lever is moved in one direction and to permit rotation of the pinion when the lever is moved in the opposite direction. 95

4. In a keyless lock comprising a relative stationary part and a part movable with one member of the structure to be locked, a fixed device within the stationary part, a hook within the movable part and adapted to engage the fixed device, a manually operated member within the movable part, means operatively connecting the manually operated member to the hook and translating the motion of the manually operated member into a motion effecting the disengaging of the hook from the fixed device and supplemental locking means operated by the hook, which supplemental locking means consists of a tongue projecting from the movable part having an aperture, and a tumbler within the stationary part to engage the aperture, such tumbler having a part engaged by the hook for the purpose set forth. 100 105 110

In testimony whereof I have signed my name to this specification in the presence of two witnesses. 115
